UNITED STATES PATENT OFFICE.

WILLIAM E. POMEROY, OF EL PASO, TEXAS.

COMBINED AUTOMATIC AND STRAIGHT-AIR BRAKE.

1,199,712.

Specification of Letters Patent. Patented Sept. 26, 1916.

Continuation in part of application Serial No. 45,883, filed August 17, 1915. This application filed February 7, 1916. Serial No. 76,591.

To all whom it may concern:

Be it known that I, WILLIAM E. POMEROY, a citizen of the United States, residing in El Paso, in the county of El Paso and State of Texas, have invented certain new and useful Improvements in Combined Automatic and Straight-Air Brakes, of which the following is a specification.

This invention relates particularly to fluid pressure brakes operated by compressed air supplied from the locomotive to brakes on the locomotive and on the several cars of the train and it relates more especially to the valve mechanism of such brakes of the kind constructed to be operated by either a reduction in the train brake pipe pressure or by an increase of pressure therein. In the operation of such valves when a reduction of the train pipe pressure is effected either by the proper actuation of the engineer's valve or by the breaking of the train pipe connections or the parting of the train, the valve mechanism is shifted to open communication between the brake cylinder and an auxiliary reservoir on each car containing compressed air, such air when transferred from the auxiliary reservoir to the brake cylinder applies the brakes and after the brakes have been applied by a proper manipulation of the engineer's valve the valve mechanism may be shifted to "lap position" and the pressure may be retained in the brake cylinder. Thereafter the brakes may be released by the engineer when he increases the pressure in the brake pipe to the proper extent to so shift the valve mechanism as to connect the brake cylinder with the exhaust and then the mechanism will assume and retain its normal or release position. This is the ordinary way of operating brakes of this general class. The brakes can also be applied by increasing the normal brake pipe pressure in such manner as to shift the valve mechanism properly to connect the train pipe directly with the brake cylinder and then the valve may be moved to lap position to retain the pressure in the brake cylinder by a slight reduction in the train pipe pressure. After this the brakes may be released by a further reduction of the train pipe pressure. In some cases provision has been made for establishing a communication between the train pipe and brake cylinder at

the commencement of the operation of supplying the brake cylinder from the auxiliary reservoir whereby some air under pressure from the train pipe may pass directly to the brake cylinder before the latter receives air from the auxiliary reservoir. In this way a quick action of the brakes is obtained as the air admitted from the train pipe quickly passes to the brake cylinder, partially fills it and said cylinder is more quickly filled or supplied with the required pressure from the auxiliary reservoir when subsequently connected therewith. Valve mechanism for the purposes above mentioned has however been quite complicated and the principal object of my invention is to simplify such mechanism and to render it more reliable in action.

My invention has been embodied in valve mechanism in general of well known construction but modified in the particulars hereinafter mentioned. Such valve mechanism made in accordance with my invention comprises as usual a slide valve operating in a slide valve chamber and connected with an actuating piston, the position of which is controlled by the air pressure in the train pipe. The slide valve chamber is connected as usual with an auxiliary air reservoir and with a brake cylinder and the organization, generally speaking, is such that the brake cylinder may be charged with compressed air either from the auxiliary reservoir or from the train pipe. More specifically, however, my slide valve is of novel construction and the ports of the valve seat and the passages between the valve chamber, the train pipe and the brake cylinder are arranged in a novel way whereby the movement of the valve is made short and speedy, the number of air passages is reduced to a minimum, and the mechanism is made to respond quickly in applying or releasing the brakes. A single passage is employed to connect the brake cylinder with the valve seat for the transfer of pressure to the brake cylinder from either the auxiliary reservoir or the train brake pipe and a single passage connects the train pipe with the valve seat for the entrance of air from the train pipe to the slide valve chamber during a straight air application of the brakes. An additional passage is, however, employed to connect the train pipe with the valve chamber

whereby air from the train pipe may pass to the brake cylinder at the commencement of a service or emergency operation of the brakes by air passing to the brake cylinder from the auxiliary reservoir. The valve is also so constructed that any excess of pressure in the auxiliary reservoir occurring during a straight air application of the brakes or when the auxiliary reservoir is being charged may be transferred to the brake cylinder instead of being allowed to escape to the atmosphere. The slide valve is of simple construction being provided with only three cavities which are so arranged as to suitably connect and cover the ports in the valve seat at the proper times.

In the accompanying drawings Figures 1, 2, 5, 7, 8 and 9 show vertical central sections of valve mechanism embodying my improvements with the parts in different positions, while the remaining figures show details of construction. Fig. 1 shows the valve mechanism in release or normal position. Fig. 2 shows the mechanism in the position it assumes when the pressure in the train pipe is somewhat reduced and air passes from the train pipe to the brake cylinder before the brake cylinder receives air from the auxiliary reservoir. Fig. 3 shows a transverse section on the line 3—3 of Fig. 1. Fig. 4 shows a transverse section on the line 4—4 of Fig. 2. Fig. 5 shows the valve mechanism in emergency or automatic position, air at this time being transferred from the auxiliary reservoir to the brake cylinder. Fig. 6 shows a transverse section on the line 6—6 of Fig. 5. Fig. 7 shows the mechanism in lap position caused by an increase of pressure in the train pipe. At this time the pressure in the brake cylinder is retained. Fig. 8 shows the valve mechanism in position to admit air directly from the train pipe to the brake cylinder. Fig. 9 shows the mechanism in lap position caused by a reduction of pressure in the train pipe, the pressure in the brake cylinder being at this time retained. Fig. 10 shows a transverse section on the line 10—10 of Fig. 9. Fig. 11 shows the slide valve in elevation, end view and bottom plan view.

The valve casing 1 may be of any suitable kind. It may be closed at one end as usual by a cap 2 between which and flanges on the casing is interposed a gasket 34 which may extend into the casing as indicated for a purpose hereinafter specified. A slide valve actuating piston 3 provided with packing rings 5 is mounted in a suitable chamber 15 in the valve casing and it is connected by a rod 4 with a slide valve 6 which valve is pressed against its seat by a spring 7 and it is adapted to move back and forth in the slide valve chamber in the usual way. The train brake pipe is connected at 29 with a cavity 9 in the valve casing and this cavity

is connected by a passage 23 with the piston chamber 15. 28 indicates a drain plug for the cavity 9 of the kind ordinarily employed. A connection is made between the slide valve chamber and the auxiliary reservoir at 26 and said valve chamber is connected by means of a groove 16 with the outer end of the piston chamber 15. The slide valve is held in normal or release position by springs 17 and 18. The spring 17 is carried by a plug 20 and extends into a flanged cap 21 engaging the adjacent end of the slide valve and also adapted to engage at 40 a shoulder on the casing. The spring 18 is carried by a plug 19 and it extends into a flanged cap 22 which engages the adjacent end of the piston 3. The inward movement of the cap is limited by a shoulder 41 in the casing. These springs operate in a manner similar to those heretofore employed in similar valve mechanism. A connection between the auxiliary reservoir and the front portion of the slide valve chamber is made through openings 25 and 24 in the cap 21 and in the part 42 of the slide valve whereby air conveyed by the groove 16 from the train pipe may pass to the auxiliary reservoir and whereby air from the auxiliary reservoir may be conveyed to the front portion of the valve chamber to act upon the piston 3.

The slide valve seat connects with the brake cylinder through a passage 12 formed in the valve casing and it connects with the cavity 9 through a passage 8. Another passage 32 connects the slide valve chamber with the passage 12 leading to the brake cylinder, but this passage is intended to prevent the overcharging of the previously charged auxiliary reservoir by permitting excess of air pressure in the auxiliary reservoir to pass to the empty or partially charged brake cylinder during a straight air application of the brakes. Exhaust takes place from the valve chamber through the passage 14, shown most clearly in Fig. 3. Another passage 31 connects the valve seat or slide valve chamber with the cavity 9. This passage is used for permitting air from the train pipe to pass to the brake cylinder at the commencement of an automatic or service application of the brakes. In the passage 8 is mounted a plug valve 30 which may be left open in order to charge at the proper time the brake cylinders from the train pipe during a straight air application of the brakes, or it may be closed so that the valve mechanism may operate solely by air transferred from the auxiliary reservoir.

The slide valve is of simple construction and it is formed with three cavities only and a single passage through it. The cavity 10 is used to connect the passage 8 with the passage 11 and for no other purpose. The cavity 27 serves to connect the valve chamber with the passage 11, while the cavity 13

serves to connect the passage 11 with the exhaust passage 14 and to also connect the passage 11 with the passage 31 leading from the cavity 9 to the valve chamber.

5 The cavities of the valve and the several passages referred to are so disposed that connection between the brake cylinder and the auxiliary reservoir and between the brake cylinder and the train pipe may be 70 established at will, and are also such that the brake cylinder may be connected with the exhaust when required. The passage 33 in the valve is so disposed relatively to the passage 32 and to the cavities in the valve 75 that it registers with the passage 32 only when the piston 3 is at the extremity of its inward movement and when the auxiliary reservoir is being charged from the train pipe. It will be understood that after an 80 automatic or emergency application of the brakes the auxiliary reservoir pressure is exhausted and when the train pipe pressure acts upon the piston 3 it moves it inward to its extreme position corresponding to that 85 illustrated in Fig. 8 and at this time air passes by way of the groove 16 through the valve chamber and to the auxiliary reservoir. The valve mechanism also assumes the 90 position shown in Fig. 8 when the brakes 95 are being applied by the use of straight air from the train pipe. At such time there is danger of the previously charged auxiliary reservoir being overcharged with air from the train pipe. At this time excessive pressure 100 may pass through the passages 33 and 32 to the empty or partially charged brake cylinder. It will thus be seen that the air at this time is not wasted but is transferred to the brake cylinder and is not lost by passing 105 to the atmosphere.

Fig. 1 of the drawings shows the valve in normal or release position. At this time the brake cylinder is connected with the exhaust 110 14 by way of the passages 12 and 11, cavity 13 and exhaust passage 14, all other ports and cavities being closed. In order to obtain an emergency or automatic application of the brakes the brake pipe pressure is reduced and the slide valve is shifted to the 115 position shown in Fig. 5 with the piston 3 in contact with the gasket 34. At this time the air passes from the auxiliary reservoir by way of the cavity 27 through the passages 11 and 12 to the brake cylinder and it 120 also passes through the passage 32. All other ports and cavities are closed. In making this application, however, before the valve has moved to the position shown in Fig. 5 it will come to the position indicated 125 in Fig. 2 at which time air will pass from the train line by way of the passage 31, cavity 13 and passages 11 and 12 to the brake cylinder and will partially charge it. Thereafter the valve will move to the position shown in Fig. 5, the port 31 being then

closed and air passes from the auxiliary reservoir to the brake cylinder in the manner before described. It will thus be seen that when making an automatic or emergency application of the brakes air first passes from the train pipe to the brake cylinder before the pressure in the train pipe is greatly reduced and the brake cylinder is partially charged, and that immediately after this the brake cylinder is completely charged from the auxiliary reservoir. In this way the mechanism is made to act very quickly and to great advantage.

In order to retain the pressure in the brake cylinder and keep the brakes applied after an automatic or emergency application the valve may be moved to the lap position shown in Fig. 9 by increasing to a sufficient extent the pressure in the train pipe. At this time there will be no communication between the brake cylinder and the exhaust or between the brake cylinder and any of the feed passages or cavities before referred to. After this the brake pressure may be relieved by slightly increasing the pressure in the train pipe and moving the valve to the position shown in Fig. 1 which is the normal or release position with the brake cylinder connected with the exhaust.

I prefer in ordinary service to use straight air for applying the brakes, keeping the auxiliary air pressure in reserve for emergencies, although it is obvious that the brakes may be applied by first drawing pressure from the auxiliary reservoir and then applying pressure from the train pipe or vice versa.

In order to operate the mechanism by straight air from the train pipe and assuming the valve to be in the normal or release 105 position shown in Fig. 1, the engineer by means of his engineer's valve properly increases the normal train pressure so as to move the valve from the position shown in Fig. 1 to that shown in Fig. 8. At this time, although the auxiliary reservoir is charged, air will not pass therefrom to the brake cylinder for operating the brakes except incidentally as hereinafter described, but air passes from the train pipe through 110 the passage 8, cavity 10 and passages 11 and 12 to the brake cylinder. When the brake cylinder is charged pressure may be retained by a suitable reduction in the train pipe pressure which will move the valve to 115 the position shown in Fig. 7, which is a lap position with all ports closed. The brakes may thereafter be released by still further reducing the train pipe pressure so as to connect the passage 11 through the 120 cavity 13 with the exhaust passage 14.

The engineer, by means of his valve, can, of course, regulate the rapidity and force with which the valve mechanism is shifted and the brakes are applied and he can suc- 130

cessively actuate his valve to effect suitable transfers of pressure.

It will be understood, of course, that when making an emergency or automatic application of the brakes, air passes from the piston chamber 15 by way of the passage 23 and cavity 9 to the train pipe, that is, the pressure is in this way reduced and the greater auxiliary pressure causes the piston 3 to move to the proper extent. When the pressures on both sides of the piston are equalized the valve stands in the position shown in Fig. 1. In like manner when making a straight air application of the brakes the increased pressure on the piston 3 exceeds the normal pressure in the auxiliary reservoir and the valve is shifted inward, the movement and the position of the valve being thus effected by an increase or a decrease in the train pipe pressure to correspond to or to rise and fall relatively to the air pressure in the auxiliary reservoir. In other words, the valve mechanism is shifted in the usual way but the construction and arrangement of the valves and valve ports is different in my valve mechanism from those heretofore used. The slide valve is of such small dimensions and of such simple construction that friction is reduced to a minimum and the movement of the valve is made relatively short and quick. It will be observed that my valve mechanism does not require the use of check valves, reducing valves, graduating valves, or the like often employed in valve mechanism of the general kind to which my invention is applied, and therefore my valve mechanism is not so liable to get out of order or to fail to operate, nor does it require such delicate adjustment or frequent repair as some other valve mechanisms employed for a somewhat similar purpose.

The valve mechanism hereinbefore described is such that the normal train pipe pressure may be quickly distributed through the valves to all the brake cylinders which prevents, to a large extent, the parting of a train. The valve mechanism acts perfectly regardless of the weight or tonnage of the car to which it is applied, or of different train pipe pressures, nor is it affected by variations in train pipe pressures on different cars. A graduated control is possible by using either automatic or straight air for a brake application.

Should it become necessary to stop a train for any reason whatever by the train men, it can be done in the usual way by releasing the normal brake pipe pressure through the conductor's valve. The engineer finding the air pressure in the train pipe and auxiliaries exhausted can make a straight air application of the brakes, thus supplementing the automatic application without losing control of the train and he can also re-

charge the auxiliary reservoirs at the same time.

It will be observed that when applying the brakes by pressure from the auxiliary reservoir (Fig. 5) air passes from the reservoir through the passage 11 and also through the smaller passage 32, but at all other times the passage 32 is closed except when the auxiliary reservoir is being charged during a straight air application of the brakes.

My improved brake valve mechanism may be employed on passenger trains or on freight trains. When the train is short and when applying the brakes by straight air from the train pipe the slide valve on each car may be moved to the position shown in Fig. 8 and in such case the brake cylinders on all the cars will be simultaneously charged to the same extent and the brakes will be simultaneously applied with equal force. Upon long trains, however, the train pipe pressure in the front portion of the train is greater than in the rearward portion thereof and unless some provision were made for preventing it the brakes would be applied much sooner on the front cars than on the rear ones. To overcome this I have so located the ports and passages that the slide valve on the forward cars will be at first moved to a greater extent than that shown in Fig. 8, while the slide valves in the brake mechanism of the rearward cars may be moved to not so great an extent. In this way the brake valves on the forward cars, after moving to the position shown in Fig. 8, will be still further moved so that the port or passage 8 of each of said valves will be slightly overlapped or somewhat choked so that the area of the passage 8 in such valve mechanism will be smaller than the area of the passages in the valve mechanism of the rearward cars where the train pipe pressure is reduced. In this way I am able to supply the brake cylinders of all the cars simultaneously with practically the same pressure and in such manner as to simultaneously apply the brakes.

When the train pipe pressure is sufficiently reduced and equalized the slide valves, which have been moved to choke the ports 8, will be shifted to the position shown in Fig. 8 so that the feed ports will then be open to their full extent in all the valves throughout the train. It will thus be seen that by my improvements the brakes on all the cars of the train, no matter what may be its length, may be simultaneously applied with equal force and there is therefore no danger of a parting of the train or a bunching of the cars as would be the case if the brakes were applied unequally.

Without going into further particulars it may be stated in general that my valve mechanism can be operated to perform all

the functions of valve mechanism of a similar class and possesses the additional advantages above specifically referred to.

I claim as my invention:

- 5 1. Combined automatic and straight air valve mechanism, comprising a casing provided with a piston chamber and a slide valve chamber and formed with a single passage leading from the brake cylinder to the slide valve chamber to convey either straight air or automatic air from the valve chamber to the brake cylinders and also with an exhaust passage for connecting the brake cylinder with the atmosphere, a piston operating in the piston chamber and subject to train pipe pressure on one side only, a slide valve connected to and moving coincidentally with the piston and which is formed with cavities, one of which is adapted to convey straight air from the train pipe to the brake cylinder, another to establish communication between the auxiliary reservoir and the brake cylinder, and a third to connect the brake cylinder with the exhaust, means controlled by the piston for permitting air to pass by way of the piston from the train pipe to the auxiliary reservoir for charging it, and a supplemental passage connecting the valve seat with the train pipe and which is controlled by one of the cavities of the valve for conveying air from the train pipe to the brake cylinder at the commencement of the automatic operation of the valve mechanism.
- 35 2. Combined automatic and straight air valve mechanism, comprising a casing provided with a piston chamber and a slide valve chamber and formed with a passage leading from the brake cylinder to the valve chamber, another passage for connecting the brake cylinder with the atmosphere, a third passage connecting the valve chamber with the train pipe, and a fourth passage also connecting the valve chamber with the train pipe, a piston operating in the piston chamber and subject to train pipe pressure on one side only, a slide valve connected to and moving coincidentally with the piston and which is formed with cavities, one of which is adapted to convey straight air from the train pipe to the brake cylinder during a straight air application of the brakes, another for establishing communication between the auxiliary reservoir and the brake cylinder, and a third for connecting the brake cylinder with the exhaust and for also at the proper time connecting the brake cylinder with the train pipe during an automatic service or emergency application of the brakes, and means controlled by the piston permitting air to pass from the train pipe to the auxiliary reservoir for charging it.
- 65 3. Combined automatic and straight air valve mechanism for air brakes provided

with means for establishing a free communication between the train pipe and the brake cylinder during a given pressure in the valve mechanism, and a restricted communication at all times between said pipe and said cylinder during an increased pressure therein, and which is provided also with means for establishing a communication between the train pipe and the brake cylinder at the commencement of an automatic application of the brakes and thereafter establishing communication between the brake cylinder and the auxiliary reservoir.

4. Combined automatic and straight air valve mechanism, comprising a casing provided with a piston chamber and a slide valve chamber and formed with a passage leading from the brake cylinder to the slide valve chamber, another passage connecting said valve chamber with the train pipe and with an exhaust passage for connecting the brake cylinder with the atmosphere, a piston operating in the piston chamber and subject to train pipe pressure on one side only, a slide valve connected to and moving coincidentally with said piston and which is formed with three channels, viz., one adapted to convey straight air from the train pipe to the brake cylinder by way of said single passage first mentioned, a second for establishing communication between the auxiliary reservoir and the brake cylinder through said first-mentioned passage, and a third for connecting the brake cylinder with the exhaust, and means controlled by the piston for permitting air to pass by way of the piston chamber from the train pipe to the auxiliary reservoir for charging it when the piston is in straight air position.

5. Valve mechanism for air brakes operated by straight air and having means for establishing a free communication between the train pipe and the brake cylinder during a given pressure in the valve mechanism, and a restricted communication at all times between said pipe and said cylinder during an increased pressure therein.

6. Combined automatic and straight air valve mechanism for air brakes provided with means for establishing a free communication between the train pipe and the brake cylinder during a given pressure in the valve mechanism, and a restricted communication between said pipe and said cylinder during an increase of pressure therein and which is provided also with means for establishing a communication between the auxiliary reservoir and the brake cylinder when the pressure in the train pipe is sufficiently reduced.

7. The combination with an auxiliary reservoir, a brake cylinder and a train pipe of a valve chamber connected with the brake cylinder, the auxiliary reservoir and the

- train pipe, and a slide valve operating in said chamber controlling the admission of air from the auxiliary reservoir to the brake cylinder and provided with an unrestricted valveless recess for connecting the train pipe with the brake cylinder at the commencement of an automatic application of the brakes and which is thereafter withdrawn from connection with the train pipe.
- 10 8. The combination with an auxiliary reservoir, a brake cylinder and a train pipe, of a valve chamber connected with the brake cylinder, the auxiliary reservoir and the train pipe, a piston chamber connected 15 with the train pipe, a piston operating therein and controlling the passage of air from the train pipe by way of the piston

chamber and the valve chamber to the auxiliary reservoir, and a slide valve operating in said valve chamber controlling the admission of air from the auxiliary reservoir to the brake cylinder and provided with an unrestricted valveless passage for connecting the train pipe with the brake cylinder at the commencement of an automatic application of the brakes and which is thereafter withdrawn from connection with the train pipe.

In testimony whereof, I have hereunto subscribed my name.

WILLIAM E. POMEROY.
